AIRCRAFT GUN MOUNT

Hubert F. Franklin, Baldwin, N. Y., assignor to
 Republic Aviation Corporation, a corporation
 of Delaware

Application September 4, 1943, Serial No. 501,224

6 Claims. (Cl. 89—37.5)

This invention relates to gun mounts, and more particularly to improvements in wing mountings for machine guns on aircraft.

The present invention is more particularly concerned with cases where the wing-type machine gun is mounted on mounts that are preferably adjustable ones, and the construction is such that the gun and its muzzle lie entirely inside the contour of the wing, the gun firing through an opening in the leading edge thereof. The adjustment is made in such manner that the position of the gun, with reference to the fore-and-aft axis of the plane, gives the desired alignment for a given flight-path angle. With the various constructions of gun mounts proposed heretofore, the opening in the leading edge of the wing has unavoidably been relatively large, among other reasons to allow for full-range adjustment of gun elevation for the respective flight-angles at different air-speeds. Such a relatively large opening appreciably weakens the wing structure and necessitates substantial reenforcement and a corresponding increase in weight. Due to aerodynamic reasons it also necessitates the employment of shutter-means for closing said opening when not in use.

With the foregoing situation in view, it is one of the objects of this invention to provide an improved gun mount of the character referred to which has all the advantages of those of the prior art, but which will entail, in addition, a substantial decrease in the diameter of fire-opening in the leading edge of the wing.

In accordance with the invention, for any and all adjustments, or angles of elevation of the gun, the respective lines of fire substantially meet, or intersect, at a theoretical focal point at, or in close proximity to, the leading edge of the wing. In short, the virtual pivot of the gun is made to lie substantially at the muzzle itself. Therefore, the fire-opening in the leading edge of the wing, need be only slightly larger than the bore of the gun.

Another feature resides in the fact that in the present improved construction, all the desired operational advantages are obtained by means of but one adjustment.

Other objects and advantages will hereinafter appear.

For the purpose of illustrating the invention, an embodiment thereof is shown in the drawings, wherein

Fig. 1 is a simplified, fragmentary, elevational view, illustrative of the operating action of the

typical prior art construction, shown for reasons made manifest hereinafter;

Fig. 2 is a simplified, side elevational view of one embodiment of my invention;

Fig. 3 is a side elevational view, partly in section, of another embodiment of my invention, the section being taken on the line 3—3 in Fig. 4;

Fig. 4 is a plan view of Fig. 3, some of the parts being removed for the sake of clearness; and

Fig. 5 is an enlarged section taken on the line 5—5 in Fig. 3.

In order to more clearly set forth the concepts and nature of the present invention, it is desirable to compare same with the most relevant of the prior art. In said prior art construction, shown in Fig. 1, the front mount 10 supports the gun 11 for elevational adjustment about a fixed pivot 12. The two extreme positions of adjustment are represented by the longitudinal center lines 14 and 15. The adjacent portion 16, of the leading edge of the wing within which the gun is mounted, is shown provided with the fire-opening 17. This opening must necessarily be relatively large, as shown, to permit the gunfire to pass through at the two extreme positions (14 and 15) and at the intermediate positions of adjustment, one of which is represented by the longitudinal center-line 8. The rear mount (not shown) may embody a screw-and-nut or other suitable construction, whereby the gun can be elevated or depressed about the pivot or pivotal supporting point 12, and fixed or locked in the desired position of adjustment. An example of such an arrangement is shown in Patent No. 1,939,699, issued Dec. 19, 1933, to Clarence F. Hofstetter.

In contrast, in the embodiment of the present invention which is shown in Fig. 2, the front and rear mounts of the gun 11a are designated generally by the reference numerals 10a and 10b, respectively. Corresponding to Fig. 1, the two extreme positions of adjustment in Fig. 2 are represented by the center lines 14a and 15a, respectively.

Connection between the gun and the front mount 10a may be made by means of two bell-cranks 16, disposed, respectively, on opposite sides of the gun and pivotally connected thereto to provide the pivot or pivotal point of support 12a, corresponding to the pivot 12 in Fig. 1. The bell-cranks 16 are pivotally connected at 17 to the respective sides 18 of the U-shaped base for the front mount, which base is fixed to some suitable part of the wing structure, as rep-

resented in the drawing. For the purpose of imparting pivotal and simultaneous movement to the members 16 about the pivot 17, a worm-gear segment 19, which meshes with a worm 20 fixed on a shaft 21, is common with respect to, and joins the members 16.

Similarly, connection between the gun and the rear mount 10b, may be made by means of two bell-cranks 22 disposed, respectively, on opposite sides of the gun. These bell-cranks are joined by a pin-and-slot connection comprising a bolt or pin 23 which has a sliding fit in a slot 24. The slot 24 is made in a lug 25 which may be integral with the gun casing. The bell-cranks 22 are pivotally connected at 26 to the respective sides 27 of the U-shaped base for the rear mount, which base is suitably secured to the wing structure. A worm-gear segment 28, which meshes with a worm 29 fixed on shaft 21, is common with respect to, and joins the members 22. The shaft 21, which may be journaled in the respective bases of the front and rear mounts, is rotated by turning a wheel 30 fixed on one end of the shaft.

The pitch of worm 20 is opposite to that of the worm 29, so that when the wheel 30 is turned in the direction to depress the muzzle of the gun, the bell-cranks 16 rotate counter-clockwise about pivot 17, and the bell-cranks 22 rotate clockwise about pivot 26. Turning the wheel in the other direction to elevate the muzzle of the gun, causes bell-cranks 16 to rotate clockwise about pivot 17, and bell-crank 22 to rotate counter-clockwise about pivot 26.

In the full-line position of the gun, the longitudinal axis of the gun is as shown at 9a. In the extreme position for maximum gun-muzzle depression, the bell-cranks 16 and 22 are in the broken-line positions shown, respectively, at 16a and 22a, and the longitudinal axis of the gun muzzle is as shown at 14a. In the extreme position for maximum gun-muzzle elevation, the bell-cranks 16 and 22 are in the broken-line positions shown, respectively, at 16b and 22b, and the longitudinal axis of the gun muzzle is as shown at 15a.

The respective dimensions of the various parts are such that in all positions of elevational adjustment of the butt or rear portion 11a of the gun, the longitudinal axis of the gun muzzle, or in other words, the line of fire, passes substantially through one and the same point 31. This theoretical focal point 31 always lies closely adjacent to the muzzle, in the direction of fire, and always lies either in, or in close proximity to, the fire-port 17a in the leading edge 16' of the wing. On account of this construction and manner of operation, with the muzzle of the gun kept back within the wing and mounted for elevational adjustment through a desired range, the opening may be retained relatively small as compared to the openings necessary heretofore. In addition, the previous necessity for providing a blast tube to protect the skin and parts from incandescent gases is entirely obviated.

In that embodiment of the invention which is shown in Figs. 3, 4 and 5, the various parts have been designated by the same reference numerals as the corresponding and respective parts in Fig. 2, but with the suffix c, and in this embodiment, the two bell-cranks 16c, which form part of the front mount, are pivotally connected to the gun 11c to provide the pivot or pivotal point of support 12c. The bell-cranks 16c are, in turn, pivotally connected at 17c to the respective sides 18c

of a U-shaped bracket for the front mount, which bracket is fixed to the front spar of the wing, as shown.

The two bell-cranks 22c are joined by a bolt or pin 23c which has a sliding fit in a slot 24c with which the gun-mount bracket 32 is provided. The members 22c are pivotally connected at 26c to the respective sides 27c of the U-shaped base 33 for the rear mount, which base is secured to the ribs of the wing.

A power shaft 21c is journalled in base 33, and is connected to an electric motor 34 and, through a universal joint 100, to a screw 21d. The collars or shoulders shown provide thrust bearings to prevent axial movement of shaft 21c with respect to base 33. The screw 21d is provided with a right-hand thread, and carries a nut 35. The other part, 21e, of this screw is provided with a left-hand thread, and is screwed into the adjacent end of a shaft 19c. The other end of shaft 19c is pivotally connected to the bell-cranks 16c, as shown. The nut 35 is provided with diametrically opposed trunnions 36 which have a sliding fit in grooves 37 in the respective faces of bell-cranks 22c, as best seen in Fig. 5.

In Fig. 3, the gun is shown in the position of maximum muzzle-depression, the longitudinal axes 9c and 14c of the gun muzzle corresponding, respectively, to the axes 9a and 14a in Fig. 2. When the motor 34 is operated in the direction to cause elevation of the gun muzzle, the nut 35 travels to the right, in Fig. 3, on the threaded part 21d of shaft 21c. This action causes counter-clockwise movement of members 22c about the fixed axis 26c. Concomitantly with the rotation of threaded portion 21d, the left-hand-pitched, threaded part 21e of shaft 21c is also being rotated, and imparts movement of the shaft 19c to the left, and thence imparts clockwise movement of members 16c about the fixed axis 17c.

As in Fig. 2, the respective dimensions of the various parts in Fig. 3 are chosen such that in all positions of adjustment of the gun 11c, the line of fire passes substantially through a focal point immediately beyond the gun structure per se, in the direction of fire. This focal point is either at or in close proximity to the very materially restricted fire-opening designated generally at 31.

In the present improved gun-mount, the handwheel 30 in Fig. 2 and the motor 34 in Fig. 3, constitute, in each case, single operating means for making all elevational adjustments. Operation of the handwheel or motor in one direction causes gun butt-depressing action of both the front and rear mounts simultaneously, whereas operation in the opposite direction causes gun butt-raising action of both mounts simultaneously. However, for any incremental adjustment, either to increase the lowering of the gun-muzzle or to increase the raising thereof, and throughout the entire operational range, the gun-butt-raising and gun-butt-depressing actions of the front mount are always effected in a lesser degree than the respective gun butt-raising and gun butt-depressing actions of the rear mount.

One of the broader aspects of the invention resides in the novel step in the method of range-changing. This step consists in bodily displacing a gun incrementally about a virtual pivot point for the entire gun, such as point 31 in Fig. 2, which point is disposed on the longitudinal axis of the gun muzzle and lies entirely beyond

and outside all the gun structure per se, in the direction of fire.

It will be understood that various changes, such as the size, shape and arrangement of the parts, may be made without departing from the spirit of this invention or the scope of the claims.

The inventive concepts and several illustrative embodiments thereof having been thus disclosed in the manner required by the statutes, what is claimed as new, is:

1. In a gun mount having spaced front and rear trunnions adjustable in elevation: a common control shaft to adjust simultaneously and differentially the elevation of said front and rear trunnions, two independent bell-cranks fulcrumed to a fixed structure, each of said bell-cranks having an upper arm pivoted to a gun trunnion and a lower arm connected to said common control shaft.

2. In a gun mount having spaced front and rear trunnions adjustable in elevation: a common control shaft to adjust simultaneously and differentially the elevation of said front and rear trunnions, two independent bell-cranks fulcrumed to a fixed structure, each of said bell-cranks having an upper arm pivoted to a gun trunnion and a lower arm connected to said common control shaft, and each of said upper arms being substantially parallel to the axis of the gun in order to act as a strut to transmit directly to said fixed structure the recoil and counter-recoil loads.

3. In a gun mount having spaced front and rear trunnions adjustable in elevation: a common control shaft to adjust simultaneously and differentially the elevation of said front and rear trunnions, two independent bell-cranks fulcrumed to a fixed structure, each of said bell-cranks having an upper arm pivoted to a gun trunnion and a lower arm connected to said common control shaft, at least the upper arm of the front bell-crank being substantially parallel to the axis of the gun in order to act as a strut to transmit to said fixed structure directly and substantially without vertical component the axial loads acting on the gun.

4. The combination with an aircraft wing having spaced front and rear internal supporting structures and a gun having spaced front and rear trunnions, said wing having a circular fire-port in its leading edge in alignment with the gun and of a diameter equal substantially to the muzzle diameter of the gun: of an adjustable gun mount comprising a front bell-crank fulcrumed to said front supporting structure and having one of its arms pivoted to the front trunnion of the gun, a rear bell-crank fulcrumed to said rear supporting structure and having one of its arms pivoted to the rear trunnion of the gun, and common differential operating means connected to the remaining arm of each of said bell-cranks to swing said bell-cranks simultaneously and differentially in opposite directions about their respective fulcrums to adjust the gun about

a virtual pivot located at or near the center of said fire-port.

5. The combination with an aircraft wing having spaced front and rear U-brackets and a gun having front and rear trunnions mounted on said brackets, said wing having a circular fire-port in its leading edge in alignment with the gun and of a diameter substantially equal to the muzzle diameter of the gun: of a vertically adjustable gun mount comprising a pair of parallel front bell-cranks fulcrumed to said front U-bracket and having their upper arms pivoted to the front trunnion of the gun and their lower arms joined together, a pair of parallel rear bell-cranks fulcrumed to said rear U-bracket and having their upper arms secured by pin-and-slot connections to the rear trunnion of the gun and their lower arms joined together, toothed helicoidal sectors formed on said joined ends of the front and rear sets of the bell-cranks, a common control shaft mounted for rotation in said U-brackets, and a pair of worms mounted on said shaft one to mesh with each of said sectors, the pitches of said worms and segments being different and opposed whereby the rotation of the shaft in either direction swings said bell-cranks simultaneously and differentially in opposite directions about their respective fulcrums to adjust the angle of elevation of the gun about a virtual pivot located at or near the center of said fire-port.

6. The combination with an aircraft wing having spaced front and rear spars and a circular fire-port in its leading edge and a gun having front and rear trunnions aligned with said port: of a vertically adjustable gun mount comprising spaced front and rear U-brackets fixedly secured to the corresponding spars, a pair of parallel front bell-cranks fulcrumed to said front U-bracket and having their upper arms pivoted to said front trunnion, a pair of parallel rear bell-cranks fulcrumed to said rear U-bracket and having their upper arms secured by a pin-and-slot connection to said rear trunnion, an internally threaded non-rotatable hollow shaft pivotally connected with the lower arms of said front bell-cranks, a nut secured against rotation between the lower arms of said rear bell-cranks, a common control screw mounted for rotation in said threaded hollow shaft, in said nut and in said rear U-bracket, and means mounted on the rear U-bracket to prevent longitudinal movement of said screw, the thread of that part of the screw cooperating with the shaft being opposed to, and of different pitch than, the thread of the part of the screw cooperating with the nut, whereby the rotation of this screw in either direction swings said front and rear bell-cranks simultaneously and differentially in opposite directions about their respective fulcrums to adjust the angle of elevation of the gun by rotating said latter about a virtual pivot located at or near the center of said fire-port.

HUBERT F. FRANKLIN.
